COMPRESSION SEALING GATE FOR
STORAGE BINS AND HOPPERS

Robert E. Heltzel, Warren, Ohio

Application December 8, 1949, Serial No. 131,762

14 Claims. (Cl. 222—505)

1

The present invention relates to improvements in compressible sealing gate for storage bins and hoppers, and has for an object to provide a gate which will serve as a sealing gasket over the discharge mouth of the hopper or bin.

Another object of the invention is to provide an improved gate structure and operating mechanism in which the gate body itself in its relation to the discharge mouth will be both water tight and cement tight.

While the improved gate and its operating mechanism may be used in any desired relation, the application of the invention will be special, being used to advantage on cement bins, concrete hoppers, or on any material that flows readily.

Broadly considered, the invention provides a gate having a compound angular swinging movement to move the same into and out of registry with the discharge mouth of the hopper or bin and a sliding movement when in such registry to move the gate into and out of sealing engagement with the edge of the discharge mouth; and to further provide means by which in opening the gate will first slide rectilinearly away from the discharge mouth and thereafter will be swung aside from such discharge mouth, and on closing the gate will be first rotated back into registry with the discharge mouth and thereafter lifted through a rectilinear motion into tight sealing engagement with the edge of the discharge mouth.

With the foregoing and other objects in view the invention will be more fully described hereinafter and more particularly pointed out in the appended claims.

In the drawings, in which like parts are denoted by the same reference characters throughout the several views,

Figure 1 is a side elevational view, with parts broken away and parts shown in section of an improved compression sealing gate for storage bins and hoppers constructed in accordance with the present invention.

Figure 2 is an end view taken from the end 2—2 of Figure 1.

Figure 3 is a side elevational view of the gate with parts broken away and parts shown in section.

Figure 4 is a vertical section taken through the gate on the line 4—4 in Figure 3.

Figure 5 is a perspective view of one of the operating arms.

Figure 6 is a side elevational view with parts broken away and parts shown in section of a

2

modified form of gate and operating mechanism.

Figure 7 is a similar view showing the parts moved to subsequent positions.

Figure 8 is a vertical section taken on the line 8—8 in Figure 6.

Figure 9 is a perspective view of one of the operating arms employed.

Referring more particularly to Figures 1 to 5 inclusive, 10 designates an operating shaft which may be rotated by any suitable means, and 11 and 12 represent links of a toggle pivoted together at 13. The links 12 are pivoted at 15 to the lower ends of operating arms 14 which are pivoted at 16 at their upper ends vertically upon the pivots 16 which outstand from opposite sides of the outlet chute 17 of a bin or hopper 18.

The arcuate gate 19 is carried by side plates or walls 20 which extend up on opposite sides of the outlet chute 17. In the upper portions of these side plates 20 are vertically elongated slots 21 and spaced above the same outwardly extending pins 22 for engagement by lugs 23 projecting at right angles from the upper portions of the operating arms 14.

Trunnions 24 projecting laterally from opposite sides of the outlet chute 17 are received in the vertically elongated slots 21 of the gate side plates 20 to permit of the gate 19 having a vertical movement toward and from the discharge mouth at the lower end of the outlet chute 17.

The gate 19 is preferably provided with a rubber or other compressible lining 25 at least around its edges which engage the edges of the discharge mouth of the outlet chute 17.

The side plates have fixedly mounted thereon casings 26 in which are slidably received the plungers 27 having their outer ends engaged against the adjacent edges of the operating arms 14. Removably or otherwise connected with the plungers 27 are stems 28 which slide through the rear end walls of the casings 26. Nuts 29 affixed to the outer ends of the stems 28 abut the outer sides of the closed end walls of the casing 26 when the plungers 27 are projected to outermost position. These nuts may be adjusted to determine this position of the plungers 27. Coil springs 30 are wound about the stems 28 in a suitable number of convolutions and have the ends thereof engaging the closed ends of the casings 26 and against the inner ends of the plungers 27. These springs are under suitable load or compression and tend to project the plungers 27 against the operating arms 14.

Roller stops 31 on the outlet chute 17 are

adapted to be abutted by vertical walls 33 of cut-out portions in the rear edges of the side plates 20 in the closed position of the gate with reference to its angular movement. Roller abutments 32 projecting out from the segmental side plates 20 are positioned to be engaged by the forward edges of the operating arms 14.

In operation it will be understood that the gate 19 and its side plates 20 can rotate on the trunnions 24 and also slide up and down vertically on said trunnions 24 due to the vertically elongated slots 21.

The closed position of the gate is shown in Figure 1 in which the gate has been raised vertically by the engagement of the lugs 23 beneath the pins 22, the vertically elongated slots 21 having moved up on the trunnions 24, and the lining 25 becoming compressed against the discharge mouth of the outlet chute 17. In this position the gate is tightly closed and no material is permitted to leak therethrough. In this position the gate is held against swinging movement to the right by the vertical walls 33 engaging the roller stops 31. The plungers 27 have been pushed into retracted positions by the operating arms 14 and held in such position by the lock afforded by the toggle links 11, 12, moving below dead center of the pivot connection 13. The operating arms 14 have moved away from the roller abutments 32.

In opening the gate, the shaft 10 is turned counter-clockwise to raise the link 11 and break the toggle lock at 13 thus pulling upon the companion links 12 and rotating the operating arms 14 to the left about their pivot points 16. During the initial movement of the operating arms 14 the lugs 23 are withdrawn downwardly from the pins 22, allowing the gate to drop by gravity and by weight of the material in the bin through a vertical distance regulated by the length of the slots 21. The gate and its lining 25 are thus freed from tight engagement with the edges of the discharge mouth of the outlet chute 17 and the gate may therefore be freely swung to the left so as to open the chute and permit discharge of the material.

This initial angular or rotary movement of the operating arms 14 does not communicate any accompanying angular movement to the gate 19 by reason of the fact that there is a lost motion between the operating arms 14 and the gate 19 due to the spacing of the roller abutments 32 from the forward edges of the operating arms 14 when those arms are in initial or closed position. Consequently the arms 14 must be rotated through a predetermined angular distance before engaging the roller abutments 32. During this lost-motion movement the operating arms 14 are assisted by the springs 30 which act to project the plungers 27 to follow the arms 14 in such initial angular movement. When the arms 14 engage the roller abutments 32 the gate 19 and its side plates 20 are entrained to move with the arms 14 and the plungers 27 have reached their maximum projection as their casings 26 are thereafter carried along with the operating arms 14. Continued rotation of the shaft 10 causes the parts 11, 12 and 14 to finally move up to the dotted line position shown in Figure 1 in which the gate 19 is shown as having reached its fully open position.

In closing, the operating arms 14 are forcibly rotated downwardly about their pivotal axes 16 by the positive rotation of the shaft 10 in a clockwise direction. In swinging down, the op-

erating arms transmit the same motion to the gate through the projected plungers 27, the springs 30 and the casings 26 which are fastened to the side plates 20 of the gate 19. These springs 5 are sufficiently strong or have sufficient load to keep the plungers 27 projected while the gate is shearing through the material which is dropping through the outlet chute 17. The load of these springs 30 is sufficiently great to hold the plungers 27 projected until the vertical walls 33 at the rear edges of the gate side walls 26 encounter the roller stops 31; whereupon the gate 19, side walls 26 and the casings 26 are necessarily arrested in angular movement. The spring-loaded 10 plungers 27 thus prevent relative angular movement between the gate and operating arms 14 during the rotary motion of the gate down to a position opposite the discharge opening of the chute. Any relative movement between the gate 20 and operating arms 14 would cause linear movement of the gate 19 toward the chute 17 which would tend to bind the gate against the chute and prevent the free swinging movement of the gate to a closing position. Thus the main function 25 of the spring-loaded plungers 27 is to maintain the gate away from the chute while such gate is being forced down and through the discharging material, and this action of the plungers 27 is only suspended when the gate side walls 30 26 encounter stops 31 whereupon the further swinging movement of the operating arms 14 in a counter-clockwise direction forces the plungers 27 inwardly and compresses the springs 30 while the arms 14 move away from the roller abutments 32 and the lugs 23 re-engage beneath the pins 22 and lift the gate to its tightly closed position over the mouth of the outlet chute 17.

Referring more particularly to Figures 6 to 9 inclusive, similar toggle links 11^a and 12^a are pivoted together at 13^a, while the links 12^a are pivoted at 15^a to the lower ends of the swinging operating arms 14^a.

The outlet chute 17^a of the bin or hopper 18^a has its lower discharge mouth controlled by the 45 arcuate gate 19^a which is supported by its side plates 20^a on the trunnions 24^a which outstand from the sides of the outlet chute 17^a and are received through vertically elongated slots 21^a in the side plates 20^a. These trunnions 24^a also serve to pivotally support the upper ends of the operating arms 14^a.

The gate 19^a is equipped with a rubber or other compressible lining 25^a and the side plates 20^a carry fixedly thereon casings 26^a of spring units 55 similar to the unit illustrated in Figure 3 and having the plungers 27^a, the stems 28^a and the nuts 29^a.

Roller stops 31^a on the outlet chute 17^a are adapted to engage the vertical walls 33^a of the side plates 20^a. Upper limit stops 34 project from the sides of the outlet chute 17^a in position to engage the forward leading edges of the side plates 20^a in the raised open position of the gate.

Pins 22^a project out from the side plates 20^a and through cam slots 23^a in the operating arms 14^a remote from their pivot points 24^a.

In operation, the gate is in its closed position in Figure 6 in which the pins 22^a occupy the upper end portions of the cam or inclined slots 23^a of the operating arms 14^a having lifted the gate 19^a to its upper closed position through the elongated slots 21^a of the side plates 20^a sliding up upon the trunnions 24^a.

Initial movement by the toggle links 11^a, 12^a

will shift the operating arms 14^a from the position of Figure 6 to the dotted position of Figure 7. In moving through this angular distance the operating arms 14^a shift the pins 22^a into the lower end portions of the cam slots 23^a thus forcing the gate 19^a and its lining 25^a down away from the discharge mouth of the bin outlet. During this initial angular movement of the arms 14^a the plungers 27^a will follow the arms under the expanding action of the springs in the casings 26^a.

By the continued angular movement of the arms 14^a around in a clockwise direction to the full line position of Figure 7 the gate 19^a now freed from the edge of the discharge opening will be angularly turned aside from such discharge opening, permitting the contents of the bin to fall into a truck or other receptacle below. This will be caused by the fact that the gate will be entrained to move with the operating arms 14^a when the pins 22^a are against the right hand end walls of the cam slots 23^a. In the fully open position, the gate side plates 20^a will strike the upper limit stops 34 as shown in full lines in Figure 7.

In closing the load of the springs in the casings 26^a will be sufficient to keep the plungers projected against the operating arms 14^a and the pins 22^a will therefore be held in the outer end portions of the cam slots 23^a to prevent the gate 19^a during its return rotary movement from moving up on the slots 21^a which would cause the lining 25^a to be scraped or ripped from the inside of the gate by the lower edges of the outlet chute 17^a. It will be understood that the thrust of the arms 14^a in closing the gate 19^a will have a high value in view of the fact that the gate 19^a must shear across through the heavy material falling through the discharge opening. However the load of the springs in the casings 26^a will be sufficiently heavy to resist such thrust and until the gate arrives at a completely closed position in a rotary sense whereupon the roller stops 31^a prevent further rotary movement of the gate and therefore the further thrust upon the arms 14^a by the toggle operating mechanism will operate to force the pins 22^a into the upper end portions of the cam slots 23^a. This will have the effect to lift the side plates 20^a and the gate vertically to compress its lining 25^a tightly against the lower edge of the outlet chute 17^a.

In both forms of the invention the toggle center in the tightly closed position of the gate is past dead center so as to form a toggle lock which resists the action of the heavy springs which might otherwise casually or accidentally shift the operating arms through the lost-motion degree of movement and such movement would defeat the purposes of the invention in that the gate would slide down to unsealed position. Particularly is this true when the device is used on cement, sand and other heavy material bins where the superposed weight of such materials is directly supported on the gate.

While I have disclosed herein the best form of the invention known to me at the present time, I desire it to be understood that I reserve the right to make changes and modifications in the herein described embodiment of the invention provided such changes fall within the scope of the following claims:

What is claimed is:

1. In a device as described, a chute having a discharge opening, a gate mounted for linear movement toward and from the discharge open-

ing and for angular swinging movement into and out of alignment with such discharge opening, an operator mounted for pivotal movement relatively to said gate, means between the gate and operator for linearly moving the gate consequent on such relative pivotal movement, an abutment on the gate in the path of movement of the operator for entraining the gate to swing in one direction with the operator, a stop positioned to arrest the closing swinging movement of said gate and to permit pivotal movement of the operator relatively to the stopped gate in which the operator moves away from said abutment, and a spring-loaded device on the gate positioned in the path of said operator to yieldably prevent relative pivotal movement of the operator relatively to the gate during the closing swinging movement of the gate and until the gate encounters said stop.

2. In a device as described, a chute having a discharge opening, a gate mounted for linear movement toward and from the discharge opening and for angular swinging movement into and out of alignment with such discharge opening, an operator mounted for pivotal movement relatively to said gate, means between the gate and operator for linearly moving the gate consequent on such relative pivotal movement, an abutment on the gate in the path of movement of the operator for entraining the gate to swing in one direction with the operator, a stop positioned to arrest the closing swinging movement of said gate and to permit pivotal movement of the operator relatively to the stopped gate in which the operator moves away from said abutment, and a spring-loaded device between the operator and gate to yieldably prevent relative pivotal movement of the operator relatively to the gate during the closing swinging movement of the gate and until the gate encounters said stop.

3. In a device as described, a chute having a discharge opening, a gate mounted for linear movement toward and from the discharge opening and for angular swinging movement into and out of alignment with such discharge opening, an operator mounted for pivotal movement relatively to said gate, means between the gate and operator for linearly moving the gate consequent on such relative pivotal movement, an abutment on the gate in the path of movement of the operator for entraining the gate to swing in one direction with the operator, a stop positioned to arrest the closing swinging movement of said gate and to permit pivotal movement of the operator relatively to the stopped gate in which the operator moves away from said abutment, a casing affixed to said gate, a plunger slidably in said casing in the path of movement of said operator, and spring means in said casing for urging said plunger toward said operator in the direction of swinging opening movement of said gate.

4. In a device as described, a chute having a discharge opening, a gate mounted for linear movement toward and from the discharge opening and for angular swinging movement into and out of alignment with such discharge opening, an operator mounted for pivotal movement relatively to said gate, means between the gate and operator for linearly moving the gate consequent on such relative pivotal movement, an abutment on the gate in the path of movement of the operator for entraining the gate to swing in one direction with the operator, a stop positioned to arrest the closing swinging movement of said gate and to permit pivotal movement of the oper-

ator relatively to the stopped gate in which the operator moves away from said abutment, a casing on said gate, a plunger mounted to reciprocate through a forward end of said casing in the path of said operator, a spring in said casing for urging the plunger against said operator, a plunger rod connected to said plunger and projecting through the opposite end of said casing, and adjusting devices on the external end of said plunger rod.

5. A device as claimed in claim 1 in which said means for linearly moving the gate comprises a pin on the gate and a lug on the operator adapted in one position to engage beneath said pin.

6. A device as claimed in claim 1 in which said means for linearly moving the gate comprises a pin on the gate and a cam slot in the operator engaging said pin.

7. In a device as described, a chute having a discharge opening, a gate mounted for linear movement toward and from the discharge opening and for angular swinging movement into and out of alignment with such discharge opening, an operator mounted for pivotal movement relatively to said gate, means between the gate and operator for linearly moving the gate consequent on such relative pivotal movement, and abutments on said gate at opposite sides of said operator and in the path thereof, one of said abutments being spaced from the operator in the closed and sealed position of the gate whereby the operator must execute a limited angular movement of its own before encountering said last named abutment to entrain the gate for swinging movement with the operator, said other abutment being spring loaded and constantly engaging the other side of said operator to oppose relative angular movement between the operator and gate during the closing swinging movement of the gate, and stop means for arresting the gate in its swinging movement after arriving opposite the discharge opening whereby further relative angular movement of the operator with respect to the gate will cause said first-named means to linearly move the gate into sealed condition against the discharge opening.

8. In a device as described, a chute having a discharge opening, a gate mounted for linear movement toward and from the discharge opening and for angular swinging movement into and out of alignment with the discharge opening, an operator mounted for movement relatively to said gate, means for linearly moving the gate consequent on such relative movement, means on said gate engageable with the operator to arrest the relative movement of the operator after the gate is moved linearly away from the opening and to entrain the gate with the operator to swing to an open position and a stop positioned to arrest the closing swinging movement of the gate when the gate is aligned with the opening and to permit movement of the operator relatively to said arrested gate in which the means on the gate is disengaged from the operator and the gate is moved linearly toward the opening.

9. In a device as described, a chute having a discharge opening, a gate mounted for linear movement toward and from the discharge opening and for angular swinging movement into and out of alignment with the discharge opening, an operator mounted for movement relatively to said gate, means between the gate and operator for linearly moving the gate consequent on such relative movement, means on said gate engageable

with the operator for entraining the gate to swing to an open position, a stop positioned to arrest the closing swinging movement of the gate and to permit movement of the operator relatively to said arrested gate in which the means on the gate is disengaged from the operator and the gate is moved linearly toward the opening, and spring means between the gate and said operator to yieldably prevent movement of the operator relatively to the gate during the closing swinging movement of the gate.

10. In a device as described, a chute having a discharge opening, a gate mounted for linear movement toward and from the discharge opening and for angular swinging movement into and out of alignment with the discharge opening, an operator mounted for movement relatively to said gate, means between the gate and operator for linearly moving the gate consequent on such relative movement, means on said gate engageable with the operator for entraining the gate to swing to an open position, a stop positioned to arrest the closing swinging movement of the gate and to permit movement of the operator relatively to said arrested gate in which the means on the gate is disengaged from the operator and the gate is moved linearly toward the opening, and means between the gate and the operator to yieldably prevent movement of the operator relatively to the gate during the closing swinging movement of the gate and until the gate encounters said stop.

11. For use with a chute having a discharge opening, a closure comprising a gate mounted for linear movement toward and from the discharge opening and for angular swinging movement into and out of alignment with the discharge opening, an operator movable relatively to said gate, means for linearly moving the gate consequent on such relative movement of the operator, means on said gate engageable with the operator after the gate moves linearly away from the opening for entraining the gate with the operator to swing the gate to an open position and a stop positioned to arrest the closing swinging movement of the gate and to permit movement of the operator relatively to said arrested gate in which the means on the gate is disengaged from the operator and the gate is moved linearly over the opening.

12. For use with a chute having a discharge opening, a closure comprising a gate mounted for linear movement toward and from the discharge opening in alignment therewith and for movement into and out of alignment with the discharge opening, an operator movable relative to said gate, means responsive to the relative movement of the operator for moving the gate linearly toward and away from the opening, means on the gate to arrest the relative movement of the operator and entrain the gate with the operator to move the gate out of alignment with the opening, means positioned to arrest the movement of the gate back into alignment with the opening and means restraining said operator from movement relative to the gate until the gate has encountered such arresting means and is arrested, at which time the operator moves relative to the arrested gate and the gate is moved linearly toward and over the opening.

13. For use with a chute having a discharge opening, a closure comprising a gate mounted for linear movement toward and from the discharge opening in alignment therewith and for movement into and out of alignment with the discharge

opening, an operator movable relative to said gate, said gate being movable linearly away from the opening during such relative movement of the operator, means on the gate to arrest the relative movement of the operator and to entrain the gate with the operator to move the gate out of alignment with the opening, means positioned to arrest the movement of the gate back into alignment with the opening, means restraining said operator from movement relative to the gate until the gate encounters such arresting means and is arrested and means between the gate and the operator for linearly moving the gate toward and over the opening during the movement of the operator relative to the arrested gate.

14. For use with a chute having a discharge opening, a closure comprising a gate mounted for linear movement toward and from the discharge opening and for angular swinging movement into and out of alignment with the discharge opening, an operator movable relative to said gate, said gate being biased to a dropped position,

means on said gate engageable with the operator to arrest the relative movement of the operator and entrain the gate with the operator to swing the gate to an open position, a stop positioned to arrest the closing swinging movement of the gate, means between the gate and the operator to yieldably prevent movement of the operator relatively to the gate during the closing and swinging movement of the gate and until the gate encounters said stop, and means between the operator and the gate for linearly moving the gate to a closed position consequent on the relative movement of the operator relatively to said arrested gate.

ROBERT E. HELTZEL.
